UNITED STATES PATENT OFFICE.

CYRUS WEST FIELD, OF WAUSEON, OHIO; CORA BELL MAXWELL, EXECUTRIX OF CYRUS W. FIELD, DECEASED, ASSIGNOR TO CORA BELL MAXWELL, OF DELTA, OHIO.

MERRY-GO-ROUND.

Application filed February 7, 1925. Serial No. 7,655.

This invention relates to an amusement apparatus and more particularly to manually operated merry-go-rounds.

The object of the invention is to provide 5 an amusement apparatus of this character of simple and strong construction, which may be turned backward when desired, without danger of breaking of the parts to render the device inoperative.

10 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

15 Referring to the drawings:

Figure 1 is an elevational view partly in section illustrating a merry-go-round constructed in accordance with the invention.

Figure 2 is a side elevational view partly 25 in section of a slightly modified form of merry-go-round.

Figure 3 is a plan view of the base carried casting, detached.

Figure 4 is a bottom plan view of the 30 beam carried sleeve.

Referring to the drawings in detail, the reference character 1^a indicates the main or supporting beam of the merry-go-round to which the frame 40 is secured, and depends 35 therefrom. Revolubly mounted on the frame 40 are the substantially small gears 3 and 4 which are connected by means of rods 19^b with the levers 8^b located adjacent to the seat 5^b in which the riders sit and operate 40 these levers to impart rotary motion to the gears 3 and 4 which mesh with the large fixed gear 2^a and by means of which revoluble motion is imparted to the beam 1^a.

The supporting base 10^a has a post 11^a 45 fixedly mounted therein and rising therefrom. A sleeve 37 is fixed to this post and is loosely encircled by the frame 40 and extends above said frame bearing at its upper end one end member 38 of a ball bearing, 50 the other member being borne by the lower end of the sleeve 15^a which is fixed to and depends from the beam 1^a and receives the upper end of the fixed post 11^a.

The gear 2^a is fixed to the fixed sleeve 37 55 by any suitable means, being here shown

keyed thereto so that it is held stationary with the result that when the gears 3 and 4 meshing therewith are turned, the beam 1^a will be correspondingly revolved and it may be either turned backward or forward without danger of injuring the mechanism.

By arranging the seats 5^b facing inwardly and longitudinally of the beam 1^a, the driving mechanism for the gears 3 and 4 may be a direct drive instead of through means 60 of a bell crank and connecting links and rods as is necessary when the seats face at right angles to the beam.

In the form of the invention as illustrated by Figures 2, 3 and 4, the apparatus is 70 somewhat similar to that shown by Figure 1 and the corresponding parts are numbered the same except that the letters "b" and "c" are used to distinguish them.

In this form, the supporting base 10^b is 75 similar to that used in Figure 1 and has rising therefrom, the fixed post 11^b with a metal casting 41 fixed to the base. This casting 41 has its upper end reduced as shown at 42 to receive the cross bar of the 80 bracket 40^a which depends from the beam 1^b. This casting 41 is fixedly connected with the post 11^b by any suitable means, a set screw 43 being here shown for this purpose and it is shown equipped with radially extending apertured feet 45 which are secured to the base 10^b by a screw.

85 This centrally disposed large gear 2^b is fixedly secured to the post 11^b by a set screw 44 or otherwise and the smaller rotary gears 90 3 and 4 mesh therewith and are mounted on the bracket 40^a. A ball bearing 50 is mounted on the post 11^b above the large gear 2^b, one member 51 being fixed to said post in any suitable manner, while the other member 42 rotates on the fixed member. The sleeve 15^b which depends from the beam 1^b is fixed thereto and has an annular flange 46 on its lower end which rests on the ball bearing member 52 and the weight of the 100 beam causes it to turn with said member 52 so that when the occupants of the seats 5^c operate the levers 8^c, the gears 3 and 4 will be rotated and engaging with the fixed gear 2^b will cause the beam 1^b to revolve 105 around the post 11^b.

I claim:

1. In a device of the character described, a base, a casting supported on the base and having an upper reduced end portion, a 110

shaft extending upwardly from the base, a beam having seats at its ends, a bracket extending downwardly from the beam and having an opening to receive the reduced 5 end portion, a gear on the shaft, a plurality of gears carried by the bracket, manually controlled means for operating the last mentioned gears, to rotate the beam, and anti-friction means for supporting the weight of 10 the beam.

2. In a device of the character described, a base, a casting supported by the base, a beam, a shaft extending through the casting

and on which the beam is mounted, an elongated bracket member having an opening 15 through which the shaft extends, said bracket member having upstanding right angled extremities secured to the beam, a plurality of gears supported by the bracket, and manually controlled means for operating 20 the gears to rotate the beam.

In testimony that I claim the foregoing as my own, I have hereto affixed my signature.

CYRUS WEST FIELD.
